UNITED STATES PATENT OFFICE.

RICHARD C. LAWTON, OF WATERBURY, CONNECTICUT.

LAMP.

SPECIFICATION forming part of Letters Patent No. 224,449, dated February 10, 1880.

Application filed January 13, 1880.

To all whom it may concern:

Be it known that I, RICHARD C. LAWTON, of Waterbury, in the county of New Haven and State of Connecticut, have invented a new 5 Improvement in Lamps; and I do hereby declare the following, when taken in connection with the accompanying drawing and the letters of reference marked thereon, to be a full, clear, and exact description of the same, which 10 said drawing constitutes part of this specification, and represents a side view, partly in section.

This invention relates to an improvement in lamps, with special reference to the standard 15 which supports the fount, the object being to make the fount adjustable as to elevation; and it consists in the construction hereinafter described, and particularly recited in the claim.

A is the base or standard, and B the fount, 20 of any desirable form or style. At the upper end of the standard a socket, C, is formed to receive a piece of cork or any similarly-compressible material, D, and in or onto this socket a cap, E, is screwed, to bear upon the material 25 D so as to compress it in the socket. Vertically through the cap and material is a perforation, corresponding to a rod, a, attached to the lamp-fount, and adapted to be moved up and down through the compressed material 30 D, which produces sufficient friction on the rod

to support the fount at any desirable elevation, and this friction may be increased or diminished by turning the screw-cap E accordingly.

The standard may be constructed so that 35 when the fount is in its lowest position, as indicated in broken lines, the spindle will be entirely hidden, or the standard may be made in telescopic form, so that at all times the spindle will be hidden.

This adjustment holds the lamp in a vertical central line over the spindle, avoiding the one-sided condition of the student-lamp, and consequent needful weighting of the base, and the construction is cheaper, more convenient, 45 and equally serviceable and desirable.

The arrangement of the parts may be reversed—that is to say, the socket may be attached to the fount and the spindle to the base; but the arrangement as described is preferable.

I claim—

The combination of the fount and base of a lamp with the socket C, compressible material D, and cap E on one part, and the spindle a 55 on the other part, substantially as described.

RICHARD C. LAWTON.
